UNITED STATES PATENT OFFICE.

REINHOLD ZINN, OF CLEVELAND, OHIO.

COMBINATION SCRAPER AND JOINER.

Application filed March 7, 1927. Serial No. 173,274.

This invention relates to brick or stone masonry tools particularly to a combination tool for working recessed mortar joints to produce the very decorative effect commonly known as raked courses. An object of the invention is to provide a simple combination tool which may be manipulated to perform substantially all the necessary operations in producing the raked course effect in any or 10 all parts of the wall.

Further objects and features of the invention will become apparent from the following description relating to the accompanying drawing wherein I have shown my preferred 15 form.

Usually separate tools are used for removing the surplus mortar from between adjacent bricks or blocks to the required depth and for afterward packing and smoothing 20 the mortar. This is because the scraping, as a matter of fact, calls for more than a simple tool in order to make speed in operating on the joints in the more open parts of the wall and in order to reach the mortar in recessed 25 corners and the like, for example where two wall faces join at a right angle, the smoothing or finishing operation also calls for more than a simple tool, because the corner recesses and the "cross" that is the vertical 30 joints, calls for a different sort of tool shape than may be used to advantage on the relatively long "line" joints, that is to say the horizontally extending joints. Consequently, as far as I know there has not been developed 35 a satisfactory tool for performing all the necessary operations in producing the raked course effect previous to my invention.

In its preferred form my invention is embodied in a triangularly shaped tool, one side member of the triangle being formed curved 40 at both ends like a hockey skate runner, this being the smoothing tool. Another side or leg of the triangle is recessed to hold a removable and longitudinally adjustable scraping tool. The third side or leg braces the 45 other two and functions as a gauge to determine the depth of the scraping tool. Incidentally, this triangle shape, while not entirely essential, is especially convenient because of clearance in using the tool in abrupt corners as when two wall faces join at right angles. The side first mentioned, namely the 50 smoothing tool portion, serves as a handle while scraping, and the recessed side serves as a handle while smoothing, these sides being preferably substantially the same size in

order that the workman is not inconvenienced by changing from one size of the handle to another.

In the drawing Fig. 1 is a perspective view 60 of the complete tool; Fig. 2 is a side elevation thereof; Figs. 3 and 4 are diagrammatic views showing the use of the tool in the joints of different character and location.

Referring in detail to the drawing, 1 is the 65 smoothing portion of the tool, 2 is the recessed handle member containing the adjustable scraping tool and 3 the strut bracing the two portions 1 and 2 and serving as a gauge for the scraping operation, as will be present- 70 ly shown.

Because the embodiment illustrated is in 75 form an open triangle, I shall, for convenience refer to the smoothing member 1, and the recessed member 2 as the legs of the triangle and the portion 3 as the base or third side. The leg 1 extends beyond the adjacent leg and the base and its smoothing surface 1^a is substantially planar for a convenient distance and the ends curve inwardly as at 1^b 80 and 1^c. It will be noted that the end 1^b is less abruptly curved than the end 1^c and is narrower from about the point 1^d to the very end. This narrow portion begins before the curve in order that the whole curved end 85 may be used for smoothing between the narrow joints as where the bricks are placed closer together than the standard mortar joint. The portion 1^b is sharpened at its end as at 1^e to serve as a scraper, reference being 90 had to Fig. 3 wherein this narrow pointed end is shown as gouging out excess mortar in a recessed corner of the wall, a portion of the horizontal mortar bed being indicated at M 95 and the bricks in the course below this mortar bed at B. The desirability of the three sided tool becomes apparent in this figure as it will be seen that considerable rotating movement may be given the tool while in this gouging out position, in order to quickly remove the necessary amount of mortar.

The opposite end of the member 1 is also sharpened as at 1^f, to serve as a scraper if desired. However, this sharpened end 1^f will be very little used because when digging 105 the mortar out of corners it is much easier to use the narrower end of the tool.

The leg 2 may be secured in any convenient manner to the leg 1 as by a screw, and similar fastening means may be provided between the side 3 and leg 1 as at 3^a, the side 3 curving outwardly as at 3^b and overlying the very end 110

of the leg 2 as at 3°, the portion 3^c being widened as shown at Fig. 1 to serve as a gauge, the gauge being wide enough to span two adjacent bricks on each side of the mortar joint. The side 3 may be secured in any convenient manner to the leg 2 as by welding. As shown in Fig. 2, the leg 2 is hollow for a considerable extent to receive a double ended scraper 5 which is longitudinally adjustable 10 and preferably made of tool steel or the like for hardness and to allow slight flexibility.

The preferred form of scraper is a flat piece of metal bent up at its ends as at 5^a. Suitably secured in a boss 2^a is a set screw 15 6 shown enlarged at its end and knurled. The inner end of the screw bears against an intermediate portion of the scraping tool and slightly bends it in such manner that the tool is borne against the bottom of the recess in 20 the leg 2 at two points, one at each side of the screw. This arrangement insures holding of the scraper rigidly in place.

It will be seen that the scraper may be projected as far beyond the gauge portion 3^c as it is desired to scrape back the mortar. In other words, the scraper may be adjusted for any depth of joint recess and this depth will be maintained by reason of the gauge portion 3^a bearing against the bricks on either side of the joint, and preventing the tool from gouging any deeper.

In using the tool, all the line courses may be effectively scraped out by long strokes of the scraper tool 5, as well as the vertical or cross joints. The joints at corners and recesses may be scraped out by the pointed end 1^a as previously mentioned and shown in Fig. 3, and during this scraping the operator holds the tool by grasping the intermediate portions of the leg 1. For smoothing the operator simply reverses the tool, grasping the intermediate portion of the leg 2, smoothing out the line joints by the member 1, the cross joints either by the portion 1^b or 1^c, preferably 1^b, as illustrated in Fig. 4.

While I have described the tool as comprising three general parts forming the legs of a triangle, it is to be understood that this tool may be made with a one piece frame as 50 by casting if found convenient, and the general shape of the tool may be altered somewhat from that shown, without departing from the spirit of my invention, reference being directed to the following claims.

55 I claim:

1. A tool of the character described, comprising an open metal frame one portion being substantially straight but rounded at one end to serve as a mortar smoothing tool, and another portion being formed to receive and support a longitudinally adjustable scraping tool, the first mentioned portion serving as the

handle while scraping, the other of said portions serving as the handle while smoothing, and means on one of said portions projecting laterally from the tool to serve as a depth gauge for the tool. 65

2. A tool of the character described comprising two mutually rigid diverging members, one member having a planular mortar smoothing surface and having one end curving inwardly from said surface toward the tool, said other member being recessed, a metal tool adapted for scraping mortar and adjustably seated in said recess, and means 70 carried by said other member for clamping the tool in adjusted position. 75

3. A scraping and joining tool for brick layers, comprising two mutually rigid diverging members, one being adapted to serve 80 as a mortar smoothing tool, the other being adapted to adjustably carry a mortar scraping tool, and rigid means joining the diverging ends of the two members and extending laterally from the scraping tool to engage brick 85 adjacent a joint being scraped by the tool whereby it serves as a depth gauge.

4. A tool of the character described, comprising a triangular open metal frame, one leg of the triangle extending beyond both 90 adjacent legs with the outer surfaces thereof curving inwardly, there being a depth gauge and a relatively adjustable scraping tool projecting beyond the gauge for scraping the surplus mortar previous to smoothing the 95 joints with said first mentioned leg, said depth gauge and scraping tool being positioned at the inter-section of said adjacent legs.

5. A tool of the character described comprising an open triangularly shaped member, one leg of the triangular member projecting beyond the adjacent legs of the triangle, and curving inwardly toward such legs, one curved portion being narrow and 100 pointed to serve as a joiner and scraper for short or narrow mortar joints, and a removable and adjustable scraping tool supported by one of said adjacent legs, and means rigid 105 with this leg for clamping the tool in adjusted position. 110

6. In a device of the character described, an open triangular member, one leg of the triangle being adapted for smoothing a mortar joint, another leg adjustably carrying a scraping tool, and the third leg extending in abutting relation to the second leg and extending laterally of the scraping tool whereby it serves as a depth gauge for the tool, said tool being reversible and there being means to 115 clamp the tool in adjusted position. 120

In testimony whereof, I hereunto affix my signature.

REINHOLD ZINN.
